US00D868822S

(12) **United States Design Patent** (10) Patent No.: **US D868,822 S**
Hajimusa (45) Date of Patent: **** Dec. 3, 2019**

(54) **DISPLAY SCREEN OR PORTION THEREOF WITH A GRAPHICAL USER INTERFACE**

(71) Applicant: **VeriFone, Inc.**, San Jose, CA (US)

(72) Inventor: **Imran A. Hajimusa**, San Jose, CA (US)

(73) Assignee: **VERIFONE, INC.**, San Jose, CA (US)

(**) Term: **15 Years**

(21) Appl. No.: **29/618,395**

(22) Filed: **Sep. 21, 2017**

Related U.S. Application Data

(62) Division of application No. 29/585,347, filed on Nov. 22, 2016, now Pat. No. Des. 802,616.

CLAIM

The ornamental design for a display screen or portion thereof with a graphical user interface, as shown and described.

DESCRIPTION

FIG. 1 is a front view of a display screen or portion thereof with a graphical user interface showing a first embodiment of my new design; and,

FIG. 2 is a front view of a display screen or portion thereof with a graphical user interface showing a second embodiment of my new design.

The outermost broken line rectangle illustrates a display screen or portion thereof and forms no part of the claimed design. The return arrow icon in FIGS. 1 and 2 forms no part of the claimed design. The remaining broken lines illustrate portions of the graphical user interface and form no part of the claimed design.

1 Claim, 2 Drawing Sheets

FIG. 1

FIG. 2
